UNITED STATES PATENT OFFICE.

HENRY W. WATSON, OF DENVER, COLORADO, ASSIGNOR OF ONE-HALF TO JAMES P. BEDFORD, OF NEW YORK, N. Y.

CONDIMENT-HOLDER.

No. 923,390.

Specification of Letters Patent.

Patented June 1, 1909.

Application filed December 20, 1907. Serial No. 407,313.

To all whom it may concern:

Be it known that I, HENRY W. WATSON, a citizen of the United States, residing at Denver, in the county of Denver and State of Colorado, have invented certain new and useful Improvements in Condiment-Holders, of which the following is a specification.

This invention relates to that class of condiment holders known as shakers which are employed for holding pepper, salt and the like, and distributing the same.

The object of the invention is to provide an improved device of the character described which is adapted to hold two different condiments, as pepper and salt, either one of which may be distributed from the holder at will.

The invention can be best set forth in connection with the accompanying drawings, which illustrate it, and of which,

Figure 1 is a side elevation of the improved shaker; Fig. 2 is a top plan view; and, Fig. 3 is a vertical axial section. Fig. 4 is a vertical axial section, similar to Fig. 3, taken through a modified form of condiment holder; and Fig. 5 is a top plan view of the holder shown in Fig. 4.

Referring to the drawing, the shaker comprises a body 1 which is divided into a plurality of compartments 2 and 3 by a partition 4. The bottom 5 of the shaker is secured to the body by means of screw threads as shown or by any other suitable means which will permit the ready removal of the bottom so that the shaker may be filled from that end. At the other end of the body is located the means for distributing the condiment from the shaker. This means comprises a stationary plate 6 which has two sets of perforations 7 and 8, each set being located over its respective compartment. Thus, the perforations 7 are over the compartment 2 while the perforations 8 are located over the compartment 3. The perforations of the sets may be of different sizes to adapt them to use with different condiments. Thus, the perforations 8 may be of a size suitable to distribute salt from the compartment 3, while the perforations 7 are smaller than the perforations 8 and adapted to distribute pepper from the compartment 2.

A cap *a* secured to the upper end of the vessel serves as a means for retaining a movable disk or plate 10 upon the stationary plate or top 6 of the vessel. The plate or disk

10 has two sets of perforations, 11 and 12, adapted to register with the sets of perforations 7 and 8, respectively, according to the position of the disk. The disk or plate 10 is of smaller diameter than the diameter of the top plate 6 of the vessel, so as to provide clearance between the periphery of said disk and the vertical wall 9^a of the cap which is secured to the outer wall of the cylinder and projects above the disk 10. The central portion of the cap is cut away, leaving an annular flange 9 which projects over the edge of the disk 10 and holds the latter against the top plate 6. The opening 9^b in the cap is of sufficient area to expose both sets of perforations in the disk to view and permit the contents of either compartment to pass out through the perforations in the top plate and disk without obstruction by the cap. A metal arm or strip 13, integral with the disk, extends through a suitable opening *c* in the vertical wall of the cap, and its outer end is bent down at an angle to form a bearing surface for the operator's finger, as shown. A spring 14 interposed between the outer end of the strip and the vertical wall of the cap normally holds the disk 10 against the vertical wall of the cap, at one side.

Normally the sets of perforations 8 and 12 are in register so that if the holder is simply inverted and shaken, without pressing the button, the contents, as salt, of the compartment 3 will be distributed. Normally the sets of perforations 7 and 11 are out of register so that the compartment 2 is closed so that none of its contents are distributed by the operation just described. If however, the button 13 is pressed, the perforations 8 and 12 will be thrown out of register, thus closing the compartment 3, while the perforations 7 and 11 are brought into registry whereupon the contents, as pepper, of the compartment 2 may be distributed. The plate 10 is guided to bring the perforations 11 and 7 into proper registry by reason of the engagement of its circular edge, opposite the button 13, with the circular wall surrounding it.

For convenience in manufacture, the plates 6 and 10 are preferably carried by a cap as shown, which is placed upon one end of the body 1 and permanently secured thereto in any suitable manner as by soldering. The permanent securing of the cap to the body has a twofold advantage. It prevents the

accidental falling off of the cap, and spilling of the contents of the holder, and insures the proper location of the perforations over their respective compartments. If the cap were removed for filling the compartments, it might be replaced in such manner that the perforations would not be properly positioned. The filling may be accomplished by removing the bottom 5.

10 In the modification shown in Figs. 4 and 5, one of the compartments is inclosed within a circular partition or cylinder 15 which at one end is secured to the plate 6', the other end of the cylinder being closed by a removable 15 cap 16. The outer wall 1' with the removable bottom 5' incloses the outer compartment which surrounds the first mentioned compartment. In the plate 6' are located the two sets of perforations 7' and 8'. The 20 perforations of the set 7' being arranged in a group at the center over the compartment inclosed by the cylinder 15, while the perforations of the group 8' are arranged outside of the set 7' and over the outer compartment 25 inclosed by the body 1'. Adapted to move across the face of the plate 6' is a plate 10', this plate having clearance and being adapted to be moved across the plate 6' by a button 13' in precisely the manner as the plate 10 is 30 moved across the plate 6 in the structure shown in Figs. 1, 2 and 3. The plate 10' carries sets of perforations 11' and 12' which are respectively adapted to be moved into and out of registry with the sets of perforations 7' and 8'. The plate 10' is normally held to one side by a spring 14', and in this position the perforations 7' and 11' are out of registry. When the plate 10' is moved to the other side, the perforations 8' 40 and 12' will be out of registry and the perforations 7' and 11' will come into registry. Where the holder is used for pepper and salt, the interior compartment is preferably employed for the pepper in which case the 45 perforations 7' and 11' will be smaller than the perforations 8' and 12' for the salt.

While in the foregoing description specific holders are described the invention is not limited, in all of its aspects, to such structures. Structures embodying the invention may be varied in numerous particulars therefore, the invention is not limited to the structures shown.

What I claim is:

55 1. In a condiment holder a cylindrical ves-

sel having a partition dividing the same longitudinally into two compartments, said vessel having a top provided with two sets of perforations, one set over each compartment, a plate, of smaller diameter than the top, 60 movable upon said top from side to side thereof, and having two sets of perforations, one set of perforations on the movable plate being adapted to register with one set of perforations in the top when the movable 65 plate is at one side, and the other set of perforations in the movable plate being adapted to register with the other set of perforations in the top when the movable plate is at the opposite side, said plate having an arm or 70 finger piece projecting laterally therefrom, a cap upon said vessel for guiding and limiting the movement of said plate, said cap comprising a cylindrical wall extending above said top and an inwardly turned flange 75 extending over the edge of said plate, said cap having a central opening of sufficient area to expose both sets of perforations in the plate and having also a suitable opening in its cylindrical wall through which said 80 arm or finger piece extends, and a spring engaging said finger piece and normally holding said movable plate against one side of the cylindrical wall of the cap.

2. In a condiment holder, a cylindrical vessel having a top provided with perforations, a plate, of smaller diameter than the top, movable upon said top from side to side thereof and having perforations adapted to be moved into and out of registry with the perforations in said top as said plate is moved from side to side, said plate having an arm or finger piece projecting laterally therefrom, a cap upon said vessel for guiding and limiting the movement of said plate, said cap comprising a cylindrical wall extending above said top and an inwardly turned flange extending over the edge of said plate, said cap having a central opening of sufficient area to expose the perforations in said 90 plate at all times and also an opening in its cylindrical wall through which said arm or finger piece extends.

In testimony whereof I affix my signature, in presence of two witnesses.

HENRY W. WATSON.
